(57) **CLAIM**

I claim the ornamental design for a coin roll opener, as shown and described.

DESCRIPTION

FIG. 1 is a perspective view of a coin roll opener, showing my new design;

FIG. 2 is a right-side elevational view thereof, the left-side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a cross-sectional view thereof, taken along line 7-7 of FIG. 5.

The broken line boundary around an internal area in FIG. 7 depicts an area that forms no part of the claimed design.
